MOUNTING MEANS FOR ELECTRICAL
APPARATUS

Roy A. Mukai, Milwaukee, Allan P. Charbonneau, Wauwatosa, Joseph F. Waldorf, New Berlin, and Robert Pearson, Milwaukee, Wis., assignors to Cutler-Hammer, Inc., Milwaukee, Wis., a corporation of Delaware

Filed Jan. 13, 1966, Ser. No. 520,444

15 Claims. (Cl. 200—168)

This invention relates to electrical apparatus adapted to be mounted on panelboards, control stations or the like.

It is an object of this invention to provide improved means for the quick and convenient mounting of electrical apparatus of the type associated with pushbuttons, panel lights or the like.

It is another object of this invention to provide improved means for mounting electrical apparatus of the one-hole panel mounting variety which apparatus consists of two major portions, a first portion such as an operator portion or the like adapted to be fastened directly to the panel and a second portion such as a separable contact block portion or the like adapted to be fastened behind the panel to the rear of the first portion.

It is a more specific object of this invention to provide mounting means of the aforescribed type which consists of means for fastening the first portion to the panel and additional means adapted to be fastened to the second portion and to be further fastened to the rearward end of the first portion.

It is another specific object of this invention to provide mounting means of the aforescribed type which enables the contact block portion or the like to be quickly and easily aligned with and attached to the rear of the operator portion or the like and permit the attachment operation to be accomplished in cramped and crowded spaces with commonly available tools.

Other objects and advantages of this invention will be evident to those skilled in the art upon reference to the following description and claims.

While the device hereinafter described is adapted to fulfill the objects stated, it is to be understood that it is not intended that the invention be confined to the particular preferred embodiment disclosed since it is susceptible of various modifications without departing from the scope of the appended claims.

In the accompanying drawings:

FIGURE 1 is a front elevational view of the exterior of a pushbutton switch assembly embodying the invention;

FIG. 2 is a side elevational view of the device of FIG. 1; FIG. 3 is a partially sectional view taken on line 3—3 of FIG. 1;

FIG. 4a is an exploded side elevational view of that portion of the apparatus which is rigidly fastened to the panel;

FIG. 4b is an exploded side elevational view of that portion of the apparatus which is removably fastened to the rear of the portion shown in FIG. 4a;

FIG. 5 is a sectional view taken on line 5—5 of FIG. 3;

FIG. 6 is a centerline sectional view of one of the parts of the assembly; and

FIG. 7 is a rear elevational view of the device with the uppermost contact block removed.

Referring to the drawings, the electrical device illustrated has an operator portion 2 adapted to be mounted in a circular hole 3 in a panel 4. The moving elements of the operator portion 2 are supported within a retainer 5 having a rectangular shaped front portion 5a and a cylindrical threaded bushing 5b extending from the rear thereof. When mounted on panel 4 the rectangular front portion 5a is on the front of panel 4 and spaced there-

2

from by a resilient gasket washer 6. A small key 7 is formed on the periphery of bushing 5b at its juncture with portion 5a to cooperate with a corresponding notch 8 formed in the edge of mounting hole 3 and to thereby properly position retainer 5 and prevent rotation thereof in panel 4. A nut 9 is threaded on the periphery of bushing 5b and is tightened against the rear of panel 4 to secure the retainer 5 in place.

The operator portion or adapter assembly 2 is preferably illustrated as having a single pushbutton 10. It is to be understood that the operator or adapter assembly 2 may include single or plural pushbuttons or rotary operators, single or plural pilot lights, or combinations thereof or the like, without affecting the principles of this invention. The pushbutton assembly 10 includes a cover 11 made of resilient plastic with tabs 11a which snap over the edges of a pushbutton plate 12 to fasten cover 11 to pushbutton plate 12.

An upper pushrod 13 and a lower pushrod 14 are securely fastened to pushbutton plate 12. These two pushrods are slidably arranged in respective apertures 15 and 16 in retainer 5. A pair of elastic seals 17 are mounted within retainer 5 adjacent apertures 15 and 16 to surround and resiliently engage pushrods 13 and 14. A pair of washers 18 cover seals 17. A pair of compression springs 19 are placed between washers 18 and plate 12 to bias the pushbutton assembly outwardly. The pushbutton assembly 10 is prevented from moving outwardly beyond the position shown in FIG. 3 by a pair of enlarged portions 20 formed on pushrods 13 and 14 which engage the rear surface of retainer 5 when in their most forward position.

The assembly to be attached to the rear of retainer 5 comprises two contact blocks 21 and 22 and a mounting device 23 therefor. These elements are illustrated in a disassembled form in FIG. 4b.

Contact blocks 21 and 22 are of identical construction, contact block 22 being inverted with respect to contact block 21 when assembled to the mounting device 23. Similar reference characters are used to identify the similar parts of the two contact blocks 21 and 22. In FIG. 3, contact block 21 is sectioned to illustrate its internal mechanism. Contact block 21 has a housing 24 and cover 25 of molded insulating material and held together by a pair of rivets 26. A plunger 27 having a contact carrier portion 28 extends through contact block 21 and communicates with the exterior thereof through apertures formed in housing 24 and cover 25. Plunger 27 is arranged to slide toward the rear against the bias of a compression spring 29 when pressed at its front end. A bridging contact 30 is supported within an aperture in the contact carrier portion 28. A compression spring 31 biases movable bridging contact 30 toward the front of contact carrier portion 28. The ends of bridging contact 30 cooperate with a pair of stationary contacts (not shown) mounted within housing 24. The ends of the stationary contact members terminate at the exterior of contact block 21 in a pair of screw type terminals 32. A pair of lugs 33 formed on opposite sides of contact carrier portion 28 engage the interior wall of housing 24 to prevent movement of plunger 28 beyond the forward surface of housing 24. Each contact block 21 and 22 is furnished with two mounting screws 34. The head of each screw is interiorly threaded to permit stacking of a plurality of similar contact blocks one behind the other. A pair of lugs 35 are formed on the front surface of each contact block and a corresponding pair of recesses 36 (FIG. 7) are formed on the rear surface to provide accurate alignment of the blocks when mounted.

It is to be understood that while the preferred embodiment illustrated incorporates two contact blocks 21 and 22 of a specific type, the apparatus attached to the

ear of mounting device 23 may instead comprise any number of other unitized or modular electrical devices such as contact blocks, pilot light transformers, potentiometer units, timer units or combinations thereof.

The mounting device 23 comprises a cover 37, a latch ring 38, and a mounting plate 39 having substantially concentric central apertures. The plate 39 has a generally rectangular central aperture through which push rods 13 and 14 communicate with the forward ends of plungers 17. Four threaded holes 40 are provided in plate 39 into which the ends of mounting screws 34 are turned to fasten contact blocks 21 and 22 to plate 39. Two pairs of notches 41 are formed in the inner edge of plate 39 to cooperate with alining lugs 35 on the front faces of the contact blocks 21 and 22. Another pair of notches 42 are provided on the inner edge of plate 39 to cooperate with a pair of lugs 43 formed on the rear of pushbutton retainer 5. Notches 42 and lugs 43 serve to prevent rotation of mounting device 23 with respect to retainer 5.

The plate 39 and cover 37 when fastened together form a housing in which ring 38 is rotatably held. The cover 37 is secured to plate 39 by four projections 44, the ends of which are peened over after insertion through corresponding holes in mounting plate 39.

A pair of inwardly extending lugs 45 are formed on the edge of the central aperture of latch ring 38. When latch ring 38 is placed over the end of the retainer bushing 5b, the lugs 45 which are slightly canted (see FIG. 6) cooperate with a corresponding pair of L-shaped camming grooves 46 formed in bushing 5b. When latch ring 38 is turned in a counterclockwise direction with respect to FIG. 5, lugs 45 engage the camming surfaces 47 in grooves 46 to firmly press the end of bushing 5b against plate 39. As the mechanism is tightened, the friction between the parts tends to bend the mechanism to lock the catch ring 38 and thereby securely fasten the mounting device 23 in place on bushing 5b.

A lug 48 on the outer periphery of latch ring 38 moves as ring 38 is rotated between the depression 49 formed in cover 37 to limit the rotation of latch ring 38. A toothed gear sector 50 is formed on the periphery of latch ring 38 to cooperate with a mating gear sector 51. Gear sector 51 is fastened together with a spring washer 52 to a shaft member 53. Shaft 53 is rotatably journaled in an aperture near the edge of plate 39 and has a rearward facing slotted head portion 54 to facilitate rotation of shaft 53 and gear sector 51 by means of an ordinary screwdriver. As can be seen in FIG. 3, the shaft 53 is positioned at the edge of the mounting device 23 so that head 54 is situated above the extremities of contact block 21 and is therefore easily accessible from the rear of the assembly by means of a screwdriver. If preferred, head portion 54 may be made in the form of a hexagon or other shape, to accommodate common wrenches.

With previously commonly available one-hole panel mounted apparatus of the heavy duty oiltight pushbutton type the usual method of assembly consists of fastening the pushbutton retainer, which might be somewhat similar to the present retainer 5, to the panel by insertion of the retainer through a hole and turning a nut or flange on the threaded bushing from either the front or back of the panel. The units similar to the present contact blocks 21 and 22 are then fastened directly to either the retainer or the nut or flange which holds the retainer in the panel hole. Examples of such conventional structures are illustrated in the C. F. Robbins Patent No. 2,568,933, issued Sept. 25, 1961 and W. F. Nolden et al Patent No. 2,930,859, issued Mar. 29, 1960. These previous designs required that if the pushbutton retainer were to be fastened to the panel before contact blocks were attached, the contact blocks must be later attached one at a time. Further, the wiring must be subsequently attached to the contact blocks in spaces which are usually crowded and confined.

With the present design the retainer 5 is first firmly secured to the panel 4. A plurality of devices such as contact blocks 21 and 22 are then attached to mounting device 23. The wiring may also be attached to terminals 52. The mounting device 23 with all attached apparatus is then easily attached to the rear of bushing 5b by the engagement of lugs 45 with camming surfaces 47 of grooves 46 caused by the turning of shaft 53 with a screwdriver. The attachment of mounting device 23 can thereby be accomplished by a single worker on one side of the panel. The mounting device 23 with the attached apparatus is quickly and easily alined and is attached without rotation of either the pushbutton retainer 5 or the mounting device 23 and attached contact blocks 21 and 22. In the event of repair, the apparatus attached to the rear of the retainer 5 may obviously be removed intact and much more easily and quickly than prior devices of the type previously described.

We claim:

1. An electrical device of the panel mounted type comprising:
  - a first portion for engaging the front of a panel and having a cylindrical bushing for extending rearwardly through an aperture in said panel to the back of said panel and said bushing having threads on the outer diameter thereof;
  - fastening means comprising a nut engaging the threads on said bushing for being tightened against the back of said panel to fasten said first portion to said panel;
  - a second portion comprising electrical apparatus mounted on the rear of said first portion; and mounting means to which said second portion is fastened and which is removably fastened to the rear of said first portion comprising:
    - a housing to which said apparatus is attached, and latching means comprising a latch member rotatably held in said housing having means thereon for engaging the rearward end of said bushing upon rotation of said latch member for fastening said mounting means to said bushing.
2. The invention as defined in claim 1 in which: said latch member comprises a latch ring; said means on said latch member for engaging the rearward end of said bushing comprises a plurality of lugs extending inwardly from the inner diameter of said latch ring; and said bushing has on its outer surface a plurality of corresponding grooves with camming surfaces engaged by said lugs upon rotation of said latch ring.
3. The invention as defined in claim 1, together with means on said bushing for engaging said housing for preventing rotation of said housing when said latch member is rotated.
4. The invention as defined in claim 1, in which said latch member comprises a latch ring and said mounting means further comprises easily accessible driving means rotatably mounted near the edge of said housing for engaging the periphery of said latch ring for causing said latch ring to rotate when said driving means is rotated.
5. The invention as defined in claim 4, in which said latch ring has a series of gear teeth formed on the periphery thereof and said driving means comprises a gear sector having teeth engaging said gear teeth on said latch ring.
6. The invention as defined in claim 5, in which: said means on said latch ring for engaging the rearward end of said bushing comprises a plurality of lugs extending inwardly from the inner diameter of said latch ring; and said bushing has on its outer surface a plurality of corresponding grooves with camming surfaces engaged by said lugs upon rotation of said latch ring.

7. An electrical apparatus of the panel mounted variety comprising:

an operator portion retaining manually operable means accessible from the front of a mounting panel and having a bushing on the rear thereof for extending from the front of said panel through an aperture in said panel to the back of said panel; 5
a nut engaging the threads of said bushing for being tightened against the back of said panel to fasten said operator portion to said panel in said aperture; 10
a second portion comprising electrical contacts operable by said manually operable means; and mounting means comprising:
a housing to which said second portion is attached having a central aperture through which said manually operable means communicates with said second portion; and
a latch member rotatably held by said housing and having means thereon for engaging the rearward end of said bushing upon rotation of said latch ring for fastening said mounting means to said bushing.

8. The invention as defined in claims 7, together with means on said bushing for engaging said housing for preventing rotation of said housing when said latch member is rotated.

9. The invention as defined in claim 7, in which said latch member comprises a latch ring and said mounting means further comprises easily accessible driving means rotatably mounted near the edge of said housing for engaging the periphery of said latch ring for causing said latch ring to rotate when said driving means is rotated.

10. The invention as defined in claim 9, in which said mounting means further comprises easily accessible driving means rotatably mounted near the edge of said housing for engaging the periphery of said latch ring for causing said latch ring to rotate when said driving means is rotated.

11. The invention as defined in claim 7 in which:
said latch member comprises a latch ring;
said means on said latch ring for engaging the rearward end of said bushing comprises a plurality of lugs extending inwardly from the inner diameter of said latch ring; and
said bushing has on its outer surface a plurality of corresponding grooves with camming surfaces engaged by said lugs upon rotation of said latch ring.

12. An assembly for mounting electrical apparatus comprising:

a support upon which said apparatus is mounted; mounting means comprising:
a member to which said apparatus is fastened and which engages said support;
a latch ring rotatably held by said member and having means thereon for engaging said support when said latch ring is placed so as to encircle said support and rotated with respect to said support;
means for rotating said latch ring comprising driving means rotatably mounted on said member engaging said latch ring and being positioned to one side of said member and beyond the extremities of said apparatus sufficiently as to be accessible for rotation by manually operable means to cause rotation of said latch ring; and
means on said support for engaging said member when said latch ring is placed over said support for preventing rotation of said member when said latch ring is rotated to engage said support;
said means on said latch ring for engaging said support being effective when said latch ring is rotated to tighten said member against said support and thereby securely fasten said mounting means to said support.

13. The invention as defined in claim 12, in which:
said means on said latch ring for engaging said support comprises a plurality of lugs extending inwardly from the inner diameter of said latch ring; and
said support has on its outer surface a plurality of corresponding grooves with camming surfaces engaged by said lugs upon rotation of said latch ring.

14. The invention as defined in claim 12, in which said latch ring has a series of gear teeth formed on the periphery thereof and said driving means comprises a gear sector having teeth engaging said gear teeth on said latch ring.

15. The invention as defined in claim 13, in which said latch ring has a series of gear teeth formed on the periphery thereof and said driving means comprises a gear sector having teeth engaging said gear teeth on said latch ring.
